[57] CLAIM

The ornamental design for a container for toys or similar article, as shown and described.

DESCRIPTION

FIG. 1 is a front view of a container for toys or similar article, showing our new design;

FIG. 2 is a side elevational view of the article of FIG. 1, the other side being substantially a mirror image thereof;

FIG. 3 is a rear elevational view;

FIG. 4 is a top plan view, the bottom thereof being substantially identical;

FIG. 5 is a top perspective view of the article of FIG. 1 illustrating the interior design thereof; and

FIG. 6 is a cross-sectional view taken generally along broken line 6—6 of FIG. 5.

FIG. 6
